Term of patent 14 years

(Cl. D52—3)

FIG. 1

FIG. 2

FIG. 3

FIG. 4

FIG. 5

Fig. 1 is a perspective view of a dispensing machine embodying my new design with portions of a cabinet shown in broken lines;

Fig. 2 is a fragmentary side elevation of the same;

Fig. 3 is a partial cross-section through the same taken along lines 3—3 of Fig. 1;

Fig. 4 is a perspective view of the same taken from a side opposite that of Fig. 1 and at a different angle of view from the latter;

Fig. 5 is a partial top plan view of the same;

The dominant features of the design reside in the portions shown in full lines.

I claim:

The ornamental design for a dispensing machine, as shown and described.
